AUTOMATIC LIQUID DISPENSING FOUNTAIN

Michael Mazzanobile, New York, N. Y.

Application April 13, 1939, Serial No. 267,565

5 Claims. (Cl. 226—128)

This invention relates to fountain liquid dispensers, and its main object is the provision of a plurality of automatically operated dispensers of a measured quantity of syrup and a measured quantity of soda water in one or more glasses at the same time. The present invention utilizes as a component part thereof the dispenser described in my prior Patent No. 2,165,398 granted July 11, 1939.

10 Another object of the invention is the provision of an automatic dispenser as above-mentioned with electrical and mechanical means for setting in operation each of the plurality of dispensers under which a glass is placed.

15 The above and other objects will become apparent in the description below, in which characters of reference refer to like named parts in the accompanying drawings.

Referring briefly to the drawings,

20 Figure 1 is a front elevational view, with parts broken away and partly in section, of the device.

Figure 2 is a cross-sectional view taken on the line 2—2 of Figure 1.

Figure 3 is a cross-sectional view taken on the line 3—3 of Figure 1, with, however, the lower portions of the liquid and soda water dispensers, shown at the top of the figure, rotated at an angle of 90 degrees, in order to illustrate the simultaneous actuation of both. This figure also shows a wiring diagram.

Figure 4 is a cross-sectional view taken on the line 4—4 of Figure 3.

Figure 5 is a fragmentary cross-sectional view taken on the line 5—5 of Figure 1.

35 Figure 6 is a fragmentary cross-sectional view taken on the line 6—6 of Figure 1.

Figure 7 is a fragmentary view similar to Figure 3, showing the electric circuit closer in inactive position.

40 Figure 8 is a cross-sectional view taken on a vertical plane through the axes of the syrup and soda water dispensers of Figure 1, with parts broken away and parts omitted, and serves to illustrate one type of valve which may be used in the device.

Referring in detail to the drawings, the numeral 10 represents a frame divided by a table or counter platform 11 and a ceiling 12 into three compartments, one above the other. The middle compartment 13 is open on all sides, the upper compartment is closed and has a removable cover 15, and the lower compartment 16 which contains the actuating mechanism, may be open or closed.

45 In the compartment 14 a plurality of syrup

5 containers 17, each having its own removable cover 18, are mounted in spaced relationship, the number of such containers being equal to the number of dispensers as will become apparent hereinafter, one such container being mounted above each dispenser. Each container 17 is supported upon the end of a pipe 19 which serves as an outlet for the container and which leads down through a petcock 20 having a nut 21 at its lower end.

10 A tank 22 adapted to hold carbonated water, rests on the floor of the compartment and is provided, adjacent each container 17, with an outlet pipe 23, which extends downward through the partition 12 and is also provided with a petcock 24 at the lower end of which is a nut 25.

15 The dispensing apparatus described in the above-mentioned copending application is attached to the nuts 21 and 25, that is, the syrup dispenser 26 has its inlet 27 threaded into the nut 21 and 20 the soda water dispenser 28 has its inlet 29 threaded into the nut 25. The operation of the dispensers 26 and 27 to cause a measured quantity of syrup and soda water, respectively, to flow into a glass when the rim of the latter is pressed 25

upward against the vertically slidable horizontal beam 30, through the outlets 31 and 32, respectively, is illustrated in Figure 8. In this illustration both the syrup and the soda water valves are shown closed, which would be the condition 30

in Figure 1. The tube 27 enters into the housing 26 through the tube 66 which threadably engages the tube 27 and projects downward beyond the same. The tube 66 is threadably engaged in a threaded opening through the top of 35

the housing 26. A similar tube 67 is threadably engaged in an opening through the bottom of the housing. A hollow stem 68, having the channel 69 therethrough, extends slidably through the tube 67 and has a horizontal head 70 capping its 40 upper end. However, a horizontal port 71 extends all the way through the stem 68 directly beneath the head 70. It is apparent that, upon raising the stem 68 by means of the beam 30, as previously described, the port 71 will rise clear 45

of the tube 67 and thus permit flow of syrup from the housing 26 into the channel 69 and out through the bottom of the latter.

45 A similar valve is provided in the soda housing 28. A hollow stem 72 having the channel 73 50 therethrough, is slidably mounted in the bottom of the housing 28 and has a head 73 thereon adapted to rest on an internal shoulder 74 of the housing, as shown, when the valve is closed. A horizontal port 75, similar to the port 71 just 55

described, passes through the stem 72 just below the head 73. When the stem 73 is raised, simultaneously with the stem 68, by the beam 30, the port 75 rises clear of the shoulder 74 so that soda water is permitted to escape from the housing 28 through the port 75 into the channel 13 and out at the lower end of the latter.

The threaded tubes 66 and 67, of the syrup container 26, are not essential to the operation 10 of the device, and they are provided for the purpose of controlling or varying the maximum degree of opening of the port 71 so that the amount of syrup permitted to flow from the housing during a single rotation of the cam 58, may be varied, 15 and this control is fully set forth in my above-identified prior patent. The valves are shown in Figure 8 for the purpose of illustration only, and it is not desired to limit the device to the use of such valves, as any other suitable valves 20 may be used which attain the same ends. The nipples 26a and 28a serve as upper limit stops to the movement of the member 30, in which position both valves of the dispensers 26 and 28 are open, and the enlarged outer flanges of the 25 outlets 31 and 32 serve as lower limit stops for the same, in which latter position both of said valves are closed. The tank 22 receives its supply through a pipe 33 from a portable cartridge, not shown.

30 In order to obtain quicker action in the discharge from the syrup dispenser of the measured amount of syrup, an auxiliary stand pipe or tube 34 is connected to an opening in the cap 35 of the syrup dispenser 26, which leads upward 35 through the partition 12 and into the syrup container 17, having its upper open end above the level of syrup within the container. A flange 36 surrounds the upper extremity of the tube 34. Surrounding the tube 34 is a second tube 37 diametrically spaced apart from the tube 34 and extending from approximately the same upper level down through to the bottom of the partition 12. A third tube 38 surrounds the tube 37 and extends from the same upper level as the 40 tube 37 down through the floor of the container 17, also concentrically spaced apart from the tube 37. Thus, there is a clearance space between the tube 34 and the tube 37, and another space between the tube 37 and the tube 38.

50 For each dispensing unit an opening is made through the table 11 in which an externally threaded sleeve 39 is locked by a knurled ring 40. An internally threaded cylindrical housing 41 is slidably mounted in the sleeve 39, and threaded 55 thereinto from the bottom is a shank 42 having a roller 43 secured in the forked end 44 thereof. The upper end of the housing 41 is widened to form a cylindrical cup 45, open at the top. A channel 46 is cut through the shank 42 from the 60 cup 45 downward and outward through the side of the shank near the fork 44. The upper portion of the channel 46 is widened and threaded, and therein an externally threaded sleeve 47 is screwed. The sleeve 47 has a flange 48 rigid at 65 its upper end. On the flange 48 a common household male plug, or any equivalent structure, 49, is secured in any desired manner, with the contact prongs 50 extending upward. The lead wires 51 from the plug pass down through and 70 out from the channel 46.

A cylindrical cap 52 is slidably mounted on the cup 45, and against its roof, but insulated therefrom, a metallic contact disc 53 is secured, whose function it is to bridge the prongs 50 in order to close a circuit therethrough. A coiled

spring 54, resting on the floor of the cup 45, normally urges the cap 52 upward to the position shown in Figure 7. A lip 55 is provided on one side of the upper edge of the cap 52 to facilitate side of a glass thereon. 5

Underneath the table 11, in the compartment 16, a horizontal shaft is rotatably supported and connected through reduction gears with an electric motor 57. Rigid on the shaft 56 in spaced-apart relationship are a number of cams 58, one such cam being provided under each roller 43. The periphery of the cam 58 is circular throughout nearly its entirety, and is provided over a short length with a cut-out 59 which rises gradually toward one end in a curve 61 which blends 15 with the circular periphery, and which at its other end 60 rises steeply and practically radially. The cut-outs 59 of all of the cams 58 are in alignment.

The wiring diagram forming part of Figure 3, 20 shows the plug leads 51 connected with the motor 57 and a supply switch 62, in simple series circuit.

The operation of the device is as follows. In the inactive position all the rollers 43 rest in 25 their respective cut-outs 59. When it is desired to fill a glass 63 with its proper amount and mixture of syrup and soda water, the glass is set on the cap 52 and pressed downward to cause the disc 53 to touch the prongs 50 against the resistance of the spring 54, and that position is maintained for a very brief interval. As soon as the circuit through the motor is thus closed, it rotates the cams 58 in a clockwise direction (Figures 2 and 3). The rollers 43 immediately begin 30 to ride up the floors 61 of the cut-outs, carrying with them the shanks 42 and all the parts supported thereon, and pressing the rim of the glass against the beam 30 and keeping the spring 54 depressed to maintain the contact of the disc 53 35 with the prongs 50. The brief interval above-mentioned is necessary in order to maintain the contact of the disc 53 with the prongs until the roller 43 has ridden upon the circular periphery of the cam, after which time the contact between 40 these parts is maintained. The cams 58 are of such size that, during a single rotation thereof, the proper quantities of syrup and soda water will have flowed into the glass to fill the latter to the proper level. Then, at the end of the 50 cycle, when the steep end 60 of the cut-out 59 reaches the roller 43, the latter will drop down almost instantaneously, thus releasing the pressure of the glass against the beam 30 and also opening the contact between the disc 53 and the 55 prongs 50, so that the motor and the cams come to a stop in the original inactive position. If any of the dispensers are not to be used, the mere fact that no glass is placed on their caps 52 keeps them from operating, as is apparent. An 60 overflow pipe 64 extends downward from the compartment 14 through the table 11, and at the upper surface of the latter an opening 65 is made into the latter to carry off also any spilled liquid from the table. The compartment 14 is 65 provided with chipped ice to keep both the tank 22 and the syrup chilled.

It is to be noted that any individual dispenser may herein still be operated by hand by simply holding the glass up against the beam 30. 70

Obviously, modifications in form and structure may be made without departing from the spirit and scope of the invention.

I claim:

1. In combination with a liquid dispenser hav- 75

ing a horizontal beam and adapted to be actuated by raising said beam, a vertically slidable member mounted under said beam, said member having a cap resiliently supported on its upper end, said cap being adapted to have a glass set thereon with the rim of the glass separated a short distance from said beam, means for raising said member and said cap and consequently simultaneously lifting said glass against said beam upon momentary depressing of said glass against said resiliently supported cap and for maintaining said member, said cap and said glass in said raised position against said beam for an interval and for releasing said member, said cap and said glass to the original position at the end of said interval, said dispenser upon the said raising of said glass against said beam being adapted to release during said interval a measured quantity of liquid into said glass.

2. In combination with a liquid dispenser having a horizontal beam vertically movable between a lower and an upper limit stop, a member vertically slidably mounted under said beam at a distance therefrom, said member having a cap slidably mounted thereon, resilient means normally urging said cap upward, a switch comprising a contact on said member and a movable contact on said cap, resilient means normally urging said contacts apart, said cap being adapted to be depressed against said resilient means to bring said contacts together, a cam having a circular periphery provided with a cut-out therein mounted under said member, said member resting on said cam with the lower end of said member registering in said cut-out when said member is in inactive position, an electric motor and a source of electric supply, said switch, said motor and said supply source being in electrical circuit, said cam being geared to said motor, said cap being adapted to have a glass placed thereon, said circuit when closed by bringing said contacts together causing said motor to rotate said cam and lift the lower end of said member upward out of said cut-out onto said circular periphery of said cam and simultaneously lifting said glass against said beam, and moving said beam against said upper limit stop, said lower end of said member upon completion of one revolution of said cam again dropping into said cut-out and releasing said glass from said lever, said resilient means simultaneously forcing said contacts apart and opening said circuit.

3. In combination with a liquid dispenser having a horizontal beam vertically movable between a lower and an upper limit stop, a member vertically slidably mounted under said beam at a distance therefrom, said member having a cap slidably mounted thereon, resilient means normally urging said cap upward, a switch comprising a contact on said member and a movable contact on said cap, resilient means normally urging said contacts apart, said cap being adapted to be depressed against said resilient means to bring said contacts together, a cam having a circular periphery provided with a cut-out therein mounted under said member, said member resting on

said cam with the lower end of said member registering in said cut-out when said member is in inactive position, an electric motor and a source of electric supply, said switch, said motor and said supply source being in electrical circuit, said cam being geared to said motor, said cap being adapted to have a glass placed thereon, said circuit when closed by bringing said contacts together causing said motor to rotate said cam and lift the lower end of said member upward out of said cut-out onto said circular periphery of said cam and simultaneously lifting said glass against said beam, and moving said beam against said upper limit stop, said lower end of said member upon completion of one revolution of said cam again dropping into said cut-out and releasing said glass from said beam, said resilient means simultaneously forcing said contacts apart and opening said circuit, said contacts comprising a disc on the underside of said cap and a prong in the upper end of said member.

4. A device as set forth in claim 2 wherein there are a plurality of said dispensers and a similar number of said members and said cams, all of said cams having their cut-outs in alignment and being geared to said motor, so that all of said dispensers are actuated simultaneously.

5. In combination with a liquid dispenser having a horizontal beam vertically movable between a lower and an upper limit stop, a member vertically slidably mounted under said beam at a distance therefrom, said member having a cap slidably mounted thereon, resilient means normally urging said cap upward, a switch comprising a contact on said member and a movable contact on said cap, resilient means normally urging said contacts apart, said cap being adapted to be depressed against said resilient means to bring said contacts together, a cam having a circular periphery provided with a cut-out therein mounted under said member, said member resting on said cam with the lower end of said member registering in said cut-out when said member is in inactive position, an electric motor and a source of electric supply, said switch, said motor and said supply source being in electrical circuit, said cam being geared to said motor, said cap being adapted to have a glass placed thereon, said circuit when closed by bringing said contacts together causing said motor to rotate said cam and lift the lower end of said member upward out of said cut-out onto said circular periphery of said cam and simultaneously lifting said glass against said beam and moving said beam against said upper limit stop, said lower end of said member upon completion of one revolution of said cam again dropping into said cut-out and releasing said glass from said beam, said resilient means simultaneously forcing said contacts apart and opening said circuit, the upper end of said member having a cup formed therein, said resilient means comprising a coiled spring resting on the floor of said cup and pressing against the roof of said cap.

MICHAEL MAZZANOBILE.
